CLAIM

The ornamental design for a travel neck pillow with accessories, as shown and described.

DESCRIPTION

FIG. 1 shows a perspective view of a travel neck pillow with accessories showing my new design;

FIG. 2 shows a front view of the travel neck pillow with accessories;

FIG. 3 shows a rear view of the travel neck pillow with accessories;

FIG. 4 shows a right side view of the travel neck pillow with accessories;

FIG. 5 shows a left side view of the travel neck pillow with accessories;

FIG. 6 shows a top plan view of the travel neck pillow with accessories; and,

FIG. 7 shows a bottom plan view of the travel neck pillow with accessories.

The shade lines in the Figures show contour and not surface ornamentation.

The broken lines shown in the Figures show portions of the travel neck pillow with accessories which form no part of the claimed design.

1 Claim, 7 Drawing Sheets
